UNITED STATES PATENT OFFICE.

STEPHEN J. BACHARDY, OF NEWARK, NEW JERSEY, ASSIGNOR OF ONE-HALF TO
ANTONIO DE DOMINICIS, OF NEW YORK, N. Y.

MONEY-PAYING MACHINE.

1,149,886.

Specification of Letters Patent. Patented Aug. 10, 1915.

Application filed April 7, 1914. Serial No. 830,257.

To all whom it may concern:

Be it known that I, STEPHEN J. BACHARDY, a citizen of the United States, residing at Newark, in the county of Essex and State of New Jersey, have invented certain new and useful Improvements in Money-Paying Machines, of which the following is a specification.

The present invention appertains to mechanical cashiers or paying machines of the type designed primarily for delivering coins in predeterminate amounts under the action of manipulative devices such as keys.

In the practical embodiment of my invention I contemplate the provision of a suitably inclosed mechanism comprising mainly a plurality of coin holders in association with which are arranged ejectors adapted to be actuated directly by pressure on keys, the latter being suitably designated and connected so as to deliver different amounts from the machine on actuation. I utilize an especially advantageous ejector mechanism including essentially a number of superposed ejector plates arranged in positions such that each may coact with one or more ejectors so that a single ejector may be actuated by a certain plate or a plurality of the ejectors may be simultaneously operated by the movement of another plate, each plate being, of course, controlled by means of a certain key of the keyboard.

I have designed peculiar guiding means for the ejector plates above referred to rendering the action of these plates free and subject to the slightest pressure on their corresponding keys.

In addition to the above I have devised special nickel and penny ejector instruments susceptible of operation independently, and one or more at a time, in respect to the ejector plates before mentioned, the nickel ejectors, however, being adapted to be operated also from the ejector plates in delivering certain amounts from the machine.

My invention also resides in certain detail features of construction simplifying generally the operation of coin delivering machines and affording an exceedingly practical construction from the standpoint of cheapness and general effectiveness.

My machine is also constructed with a special view to use thereof on street cars for facilitating the making of change by con-

ductors and may be readily adapted for operation in connection with turnstile apparatus.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a perspective view of a machine embodying the essential features of the invention. Fig. 2 is a top plan view of the same, the casing removed. Fig. 3 is an end view showing more fully the parts illustrated by Fig. 2. Fig. 4 is a rear view bringing out more clearly the ejector levers, and the arrangement of the ejectors for the various coin holders, the casing being shown in section. Fig. 5 is a front view of the machine showing the coin receptacles in section and the coin chute partly broken away and in section. Fig. 6 is a sectional view taken about on the line 6—6 of Fig. 5. Fig. 7 is a fragmentary sectional view of the dollar ejector means. Fig. 8 is a fragmentary view illustrating more fully the arms offstanding from the nickel ejectors and operable by the ejector plates. Fig. 9 is a detail view of the twenty cent ejector plate. Fig. 10 is a similar view of the ninety cent ejector plate. Fig. 11 is a rear view showing more clearly the arrangement of the ten cent ejectors. Fig. 12 is a sectional view on the line 12—12 of Fig. 11. Fig. 13 is a fragmentary plan view bringing out more clearly the arrangement of the parts illustrated by Fig. 8. Fig. 14 is a vertical sectional view taken about on the line 14—14 of Fig. 8. Fig. 15 is a fragmentary sectional view bringing out more clearly the arrangement of the ejector plates relative to the ejector heads on the ejectors.

A in the drawings denotes the casing of the machine and the top A' of said casing, as shown in Fig. 6, may be hinged at the back of the machine as at 1 so that it may be lifted and thus opened to permit of ready access to the ejector mechanism arranged immediately below said top. At the front upper portion of the machine are located the coin holders 2 which are formed in a coin section B detachably secured on the frame C of the machine. Below the coin holders 2 so as to receive coins ejected from the latter, is lo-

cated the coin chute D which inclines downwardly toward one end of the machine so as to deliver the coins at the delivery point D' where the chute terminates in a spout-like portion. It is contemplated that the chute D may be arranged so as to incline toward either end of the machine as might be found desirable for different purposes, or the chute might terminate at the front of the machine above the keyboard, this being immaterial to the invention.

At the front lower portion of the machine is arranged the keyboard which comprises a series of keys 3 having the vertical stems 3' and a second series of keys 4 carried directly by the horizontal arms of ejector levers 5. The stems 3' are really extensions of the corresponding ejector levers 5. Certain of the levers 5 are mounted loosely on the axis 6 and others are loosely mounted on the axis 7, the axis in each instance consisting of a bar or rod extending longitudinally of the machine and suitably supported at its ends. As will be noted on reference to the drawings, all of the keys 3 and 4 which control amounts of ten cents or greater valuation are connected with the levers 5 which coöperate with ejector plates 8, the latter being shown quite clearly in Figs. 9 and 10 as consisting of a body arranged lengthwise of the machine and formed with an approximately central guide member 8^a extending rearwardly and forwardly from said plate and formed with elongated guiding slots 8^b. Each plate 8 is provided also with one or more ejector lugs 8^c and with an apertured rearwardly extending arm 8^d through the aperture of which the vertical arm of a coacting lever 5 extends to establish an interlocking connection between said arm and the lever.

The various plates 8 are superposed as shown in Figs. 3 and 6 quite clearly and each plate is free to move independently of the plates adjacent thereto, under the actuation of the particular key and lever connected with said first named plate. Also, owing to the arrangement shown, by depressing two or more keys a corresponding number of plates 8 will be actuated simultaneously so a transaction of the machine is not confined to actuations of the plates 8 one at a time only. Fig. 4 plainly shows how each lever 5 is connected with one certain plate 8 and since the points of connection must necessarily be arranged nearer or farther from the center of the ejector plate, provision must be made for a mounting of the several plates 8 whereby the movement of each will be free and easy under practical conditions of service, notwithstanding that the point of pressure of the actuating lever for the plate may be a considerable distance away from the center of resistance offered to the plate by the movement of the ejectors

9. The ejectors 9 are provided for the several coin holders 2 excepting, however, the nickel and penny holders which have special ejectors to be later described. Each ejector 9 is adapted at its forward end to positively engage the lowermost coin in its associated coin holder 2 and force said coin into a position in which it will drop into the chute D and be delivered from the machine. At its rear end each ejector 9 is formed with a head 9^a which with the body of the ejector has a sort of T form. The head 9^a is sufficiently long vertically to be arranged in the path of the ejector lugs of the various plates 8, the number of plates 8 adapted to coöperate with a predetermined ejector head 9^a depending, of course, upon whether said plates have ejector lugs 8^c opposite the head. An example will make clear this point of construction, the ejector plate 8 in Fig. 9 being shown as having a single lug 8^c. Said lug 8^c is coöperative with two ejectors 10 and 11 that are capable of simultaneous movement by engagement by the lug 8^c to eject from the ten cent coin holder 2 two dimes. On the other hand, the plate 8, as shown in Fig. 10, is formed with four lugs 8^c so arranged that the fifty cent, twenty-five cent, the ten cent ejector 10 only, and a member on the five cent ejector are in the paths of movement of said lugs whereby when the plate 8 is actuated ninety cents will be ejected from the several holders 2 mentioned and delivered by the chute D.

Reverting to the mounting of the ejector plates 8, it will be observed that only a slight movement of these plates is necessary and said movement is limited by means of rollers 12 and 13. The roller 12 passes through the slot 8^b at the front ends of the guide members 8^a of all the superposed plates 8 and the roller 13 passes through the corresponding rear slots of all said plates. Not only do the rollers 12 and 13 limit the extent of movement of the plates 8 but these rollers form anti-friction devices intermediate the plates and the supporting framework of the machine whereby to render the movement of each plate under the actuation of the key, very free and easy as required. Fig. 6 brings out clearly the manner in which the plates 8 are guided in their to and fro movement, and the front roller 12 will be seen to be held in place by a fastening member 14 which coöperates to secure the removable coin section B of the machine upon the framework C.

A single ejector is utilized for each of the coin holders 2 designed to receive one dollar, fifty cent and twenty-five cent pieces. The ten cent coin holder 2, however, is provided with a double ejector mechanism comprising the ejectors 10 and 11 previously referred to, the ejector 11 being disposed above the ejector 10. If the ejector 10 is moved alone

5 a single coin will be ejected from the ten cent holder 2 and such movement is allowed owing to the fact that the rear end of the ejector 11 is cut away at 11^x so that the head 10' of the ejector 10 may move forwardly with the ejector 10, without influencing the ejector 11. This is not true, however, in respect to the ejector 11, the head 11' of which overlaps the rear end of the 10 ejector 10 as seen in Fig. 11 so that when for instance the ejector lug 8^c of the plate 8 of Fig. 9 engages the head 11' to cause ejecting movement of the ejector 11, said head abutting as it does with the ejector 10 will 15 cause the two ejectors 10 and 11 to move forward simultaneously and eject two coins from the dime receptacle or holder 2. The arrangement of the dimes ejector mechanism is desirable because by operating a single 20 ejector plate 8 two dimes may be delivered from a single coin holder, or one dime, as desired, to make up amounts such as twenty-five cents and fifteen cents, respectively.

I contemplate the provision intermediate 25 the frame C and the heads of the various ejectors 9, 10 and 11 of coiled springs 16 which coöperate to normalize the ejectors after a transaction of the machine. The normalizing action is facilitated also owing 30 to the provision of other coiled springs 17 which are connected with the frame of the machine and with the horizontal arms of the levers 5 which operate the ejector plates, the tendency of the springs 17, see Fig. 3, 35 being to pull upwardly on said arms and thereby act to pull the ejector plates rearward and maintain them in such positions.

I will now proceed to describe the system 40 of penny and nickel ejectors used in the machine, referring especially to Figs. 3, 4, 8, 13 and 14. The penny ejectors are seen in Figs. 3 and 4 as consisting of four superposed members 18, 18^a, 18^b and 18^c each pressed rearwardly and thus held in its normal position by a spring 16. The ejectors 45 18^a, 18^b and 18^c have downwardly projecting heads only located in overlapping positions while the uppermost ejector 18 has an upwardly and downwardly extending head (see Fig. 3). The penny key 4 has the vertical arm of its lever 5 adapted to engage the head of the lowermost ejector 18^c to move this ejector alone and eject one penny. The two cent key 3 has its lever 5 arranged 50 to engage the head of the ejector 18^b to thus actuate said ejector and also the ejector 18^c, the latter being overlapped by the head of ejector 18^b. Thus it is that the three cent key will operate by the same principle of 55 action the three lowermost penny ejectors, and the four cent key will operate all of the penny ejectors.

60 While the penny ejectors are susceptible of operation singly or collectively independently of the ejector plates 8, the nickel ejec-

tors which are superposed like the penny ejectors have means whereby certain of the ejector plates 8 may actuate one or two of said nickel ejectors. The manner in which the levers 5 engage directly with the rear ends of the penny ejectors is shown in Fig. 4. The upwardly extending portion of the head of the ejector 18^a is located at one side of the corresponding portion of the ejector 18. On the other hand, the ejector 18^b has a head not only extending down to overlap the head of the ejector 18^a but also a laterally extending portion 18^b' in a convenient location for engagement by its lever 5. The uppermost ejector 18 is cut away at its rear end to permit the portion 18^a' of the head of the ejector 18^a to move forwardly while the ejector 18 is stationary.

The nickel ejectors are numbered 19, 19^a, 19^b and 19^c and have corresponding heads 19', 19^a', 19^b', and 19^c' having the overlapping arrangement previously described as well as the lateral portions referred to in connection with the penny ejectors. However the ejector 19^b has a lateral arm 20 extending therefrom and the ejector 19^c has a similar arm 21 projecting laterally therefrom. These arms 20 and 21 are formed with auxiliary heads 20' and 21' respectively which heads are adapted to be engaged by lugs on certain of the ejector plates A. Thus it is that on depression of the twenty-five cent key a lug 8^c on a certain plate 8 will engage and operate the dimes ejectors 10 and 11 on movement of the plate 8. At the same time a different lug 8^c of said certain plate will engage the arm 21 of the lowermost nickel ejector 19^c so as to actuate said ejector and compel the delivery of a five cent piece along with the delivery of the two dimes ejected by the parts 10 and 11. In the event it is desired to eject ten cents from the machine depression of the ten cent key will actuate a plate 8 having a lug 8^c capable of engaging the auxiliary head 20' of the arm 20 and the two lowermost nickel ejectors 19^b and 19^c will be operated to deliver two nickels from the machine. The manner in which this principle of operation is carried out in respect to other transactions of the machine necessitating the delivery of amounts requiring the ejection of coins from the different receptacles, will be evident in view of the foregoing. It is furthermore evident that if desired instead of the arms 20 and 21 being provided on the ejectors 19^b and 19^c respectively said arms might be formed on certain of the plates 8 and extend over in rear of the ejectors 19^b and 19^c, and the same result would be accomplished.

Referring to Fig. 7, it will be noted that a special dollar ejector is utilized being designated 22 and having the head 23 at its rear end in coöperation with spring 16. The

head 23 is engageable by the upper arm of one of the levers 5 and in this way the dollar coins will be ejected by direct action of the lever 5 on the ejector 22, and without the interposition of any ejector plate 8 such as those above described.

Having thus described by invention, what I claim as new is:—

1. In a money paying machine, the combination of a plurality of coin holders, ejectors associated with said holders, operating means for said ejectors including a plurality of ejector plates, each plate having means to engage one or more ejectors, each of said 10 ejector plates comprising a central guide member, rollers passing through the guide member of each ejector plate at spaced intervals to direct the latter in its movement, and manipulative devices coöperating with the 15 plates to cause actuation of the same and the ejectors associated therewith.

2. In a money handling machine, the combination of a frame, a coin section removably fitted to said frame, a coin chute beneath said coin section, the coin section embodying a plurality of coin holders, ejecting mechanism coacting with the said coin holders and comprising a plurality of superposed ejector plates resting one upon the 25 other, rollers passing through the ejector plates to guide and limit the same in their movement, a fastening connecting the coin section with the frame and passing through one of said rollers to form the axis of the 30 latter, and manipulative devices for operating said ejector plates.

3. In a money handling machine, the combination of a coin section embodying a plurality of coin holders, a supporting frame 40 for said holders, a plurality of ejectors associated with the holders, a plurality of ejector plates coacting with a certain number of the ejectors above mentioned, manipulative devices to actuate the ejector plates, other manipulative devices arranged to co-operate directly with other of the ejectors, and arms extending laterally from certain 45 ejector plates and disposed lengthwise of the machine in rear of the ejectors last referred to, whereby the last mentioned ejectors are 50 operable directly from their manipulative devices, or operable by the manipulative devices first mentioned through the medium of the ejector plates having said arms.

4. In a money paying machine, the combination of a plurality of money holders, ejector mechanism associated therewith and including an ejector arranged to coöperate 60 with each holder, a plurality of superposed ejector plates resting one on the other, each plate being provided with means to act on one or more ejectors to cause ejecting movement of the latter, actuating means for said plates, means for normalizing the ejectors 65 after a transaction of the machine, a guide

member engaging all of the ejector plates to direct the same in their movement, and means coacting with said guide means to prevent unauthorized displacement of the ejector plates.

5. In a money paying machine, the combination of a plurality of money holders, ejector mechanism associated therewith and including an ejector arranged to coöperate with each holder, a plurality of superposed 70 ejector plates, each plate being provided with means to act on one or more ejectors to cause ejecting movement of the latter, actuating means for said plates, means for normalizing the ejectors after a transaction of 80 the machine, each ejector plate being provided with a guide member, and spaced anti-friction devices each of which interlocks the guide members of all of the ejector plates whereby to direct the same in their movement, and actuating means for the ejector plates.

6. In a money paying machine, the combination of money holders, ejectors associated therewith, a plurality of superposed 90 ejector plates each adapted to coact with one or more ejectors to operate the latter, each of the ejector plates being provided with a guide member having spaced slots therein, and guiding rollers passing through the 95 slots of said guide members whereby to direct the movement of the ejector plates, and actuating means for the ejector plates.

7. In a money paying machine, the combination of money holders, ejector mechanism for said holders comprising ejector plates, each plate adapted to control the delivery of money from one or more holders, means for operating the ejector plates, other money holders, independent ejectors controlling 100 the delivery of money from the last named holders, separate means for operating the last mentioned ejectors, and means intermediate said ejectors and the ejector plates whereby the ejectors may be operated 105 on operation of the ejector plates, said intermediate means comprising arms capable of transmitting the movement of the ejector plates to said ejectors.

8. In a money paying machine, the combination of money holders, ejector mechanism for said holders comprising ejector plates, each plate adapted to control the delivery of money from one or more holders, means for operating the ejector plates, other money holders, independent ejectors controlling 115 the delivery of money from the last named holders, separate means for operating the last mentioned ejectors, and means intermediate said ejectors and the ejector plates whereby the ejectors may be operated 120 on operation of the ejector plates, said last mentioned means comprising arms offstanding from certain of the ejectors, the ejector plates having means to engage said arms 125 130.

whereby movement will be imparted to said ejectors simultaneously with the movement of certain ejector plates.

9. In a money paying machine, the combination of a frame, a coin section removably mounted on said frame and comprising coin holders, ejector mechanism associated with said coin holders and including a plurality of ejector devices, means for operating the ejector devices, and fastening means connecting the coin section with the frame and coöperating with the ejector devices to direct the latter in their movement.

10. In a money paying machine, the combination of a frame, a coin section remov-

ably mounted on said frame and comprising coin holders, ejector mechanism associated with said coin holders and including a plurality of ejector devices, means for operating the ejector devices, a member for fastening the coin section to the frame, and an anti-friction device carried by said member and coöperating with the several ejector devices to guide the latter in their movement.

In testimony whereof I affix my signature 25
in presence of two witnesses.

STEPHEN J. BACHARDY.
